[57] CLAIM

The ornamental design for a cabinet, as shown and described.

DESCRIPTION

FIG. 1 is a perspective view of a cabinet showing my new design;

FIG. 2 is a top plan view in closed condition;

FIG. 3 is a left side elevational view thereof;

FIG. 4 is a right side elevational view thereof;

FIG. 5 is a rear elevational view thereof;

FIG. 6 is a bottom plan view thereof;

FIG. 7 is a front elevational view thereof;

FIG. 8 is an elevational view of a second embodiment of the interior;

FIG. 9 is an elevational view of a third embodiment of the interior; and,

FIG. 10 is an elevational view of a fourth embodiment of the interior.

The doors are removed in FIGS. 8-10, inclusive, for convenience of illustration.
